T. OLSEN ET AL

HOG SINGER

Filed Sept. 24, 1925

UNITED STATES PATENT OFFICE.

THOMAS OLSEN, OF TORONTO, ONTARIO, AND JOHN W. MAY, OF WINNIPEG, MANITOBA, CANADA, ASSIGNORS TO HARRIS ABATTOIR COMPANY, LIMITED, OF TORONTO, ONTARIO, CANADA.

HOG SINGER.

Application filed September 24, 1925. Serial No. 58,414.

The principal objects of the invention are, to effect a material saving in the cost of singeing and scraping hogs in the process of preparing the carcasses for the market.

5 It has been the practice to pass the carcasses of hogs through a vertical flue maintained at a definitely defined temperature for the purpose of driving the gelatine from the hide and otherwise cleansing the exterior of 10 the carcass and the cinder formed on the hide has been scraped off by hand.

The present invention conserves the heat using the very minimum and thoroughly cleanses the carcass after it has been singed.

15 The principal feature of the invention consists in the novel construction of a furnace having a horizontal heating chamber provided with entrance chambers at the ends, having double swing doors and a carrier 20 for carrying the carcasses therethrough, and in the novel construction and arrangement of a plurality of rotatable brushes at one end of the furnace between which the carcass passes after passing through the 25 furnace.

In the accompanying drawings, Figure 1 is a side elevational and part mid-sectional view of our improved device.

Figure 2 is a plan sectional view taken 30 through the line 2—2 of Figure 1.

Figure 3 is an end elevational and part sectional view taken through the line 3—3 of Figure 1.

Figure 4 is an enlarged sectional and elevational detail of the trackway, trolley and endless chain arrangement for carrying the carcasses through the furnace.

In the construction herein shown, the furnace 1 is a long narrow horizontal type 40 having the side walls 2 joined in an arch over the top.

At each end of the furnace there is arranged a compartment 3 separated from the main heating chamber 4 by the double swing 45 doors 5 which are preferably formed hollow and water cooled.

The outer sides of the compartment 3 are closed by double swing doors 6 which may also be water cooled, if desired.

50 A suitable arrangement of heating means is provided and is here shown in the form of oil burners 7 which enter through side openings 8 in the side walls of the furnace and are fed by the oil and air pipes 9 and 10.

A flue 11 extends from the top of the main 55 heat chamber 4 and branch flues 12 lead from the end compartments and connect with the main flue.

This arrangement of flues carries off all smoke and odor from the furnace. 60

A trackway 13 extends through the centre of the furnace, being suspended a short distance below the top, preferably on hollow brackets 14 which are connected to cross pipes 15 through which water is circulated 65 from the side pipes 16.

The hollow brackets are connected to a longitudinal pipe 17 which forms or carries a trackway. This arrangement of a water cooled trackway is necessary on account of 70 the high temperature maintained in the furnace in order that the trackway will not be burnt out.

A frame 18 is arranged outside of the furnace and carries the vertical shafts 19 on 75 which are secured the sprocket wheels 20.

The inward pair of sprocket wheels are arranged close to the vertical centre line of the furnace and slightly below the level of the trackway, while the outer pair of 80 sprockets are arranged outside of the furnace wall.

An endless chain 21 is mounted on these sprockets and is provided with a plurality of spurs 22 which extend under the trackway and are adapted to engage the trolleys 23 mounted on the trackway upon which the carcasses are supported. 85

The trackway 13 extends beyond the ends of the furnace. 90

The hogs to be singed are hung on trolleys at one end of the furnace and moved up to the outer doors and a spur on the endless chain 21 engages the trolley and moves the carcass into the end compartment. 95

The outer swing doors close before the carcass passes through the compartment 3 so that when the inner doors are opened the intense heat from the furnace will be closed in by the outer doors. 100

The heat and smoke escaping from the inner chamber of the furnace when the inner doors are opened, escapes through the branch flue following the closing of the inner doors. 105

The carcass passes through the furnace and striking the inner swing doors at the other end passes into the end compartment

and the inner door is closed before the carcass strikes the outer door and the fumes are carried away by the branch flue.

Arranged above the trackway at the discharge end of the furnace are a plurality of spray nozzles 24 connected with the water pipes which are carried through the heat chamber and the hot water is sprayed downwardly over the carcasses as they emerge 10 from the furnace.

Secured to the side members of the frame upon the vertical spindles 25 are the swinging frames 26 which extend inwardly toward each other and in these frames are rotatably mounted the cylindrical brushes 27.

The brushes 27 are rotated by sprocket chains 28 driven from the spindles 25 which are operated by means of suitable intermeshing gears 29 operated from the horizontal 20 shaft 30.

The swing frames 26 are spring held inwardly to the position shown in Figure 2 and as the carcass of the hog emerges from the furnace it moves into contact with the 25 first pair of brushes and these brushes which are provided with stiff bristles, preferably wire, spread apart through the pivotal arrangement of the frames to allow the carcass to pass between them, while the rotation of 30 the brushes cleanses off the cinder material drawn from the skin by the heat.

Three sets of brushes are herein shown as sufficiently necessary to thoroughly cleanse the carcass with the assistance of 35 overhead sprays of hot water, but of course any desirable number may be used.

A device such as described operates very efficiently as the carcasses are not taken from the floor where the first operations 40 thereon take place, as has hitherto been the case, necessitating the arrangement of a killing floor at a level below the others.

The horizontal arrangement of the furnace conserves the heat, consequently it 45 allows for less fuel being used and the scraping of the carcasses coming from the furnace is very effectively accomplished by the rotary brushes.

What we claim as our invention is:—

50 1. A hog singer, comprising a furnace having a longitudinally extending horizontal heat chamber, sets of doors at the opposite ends of said heat chamber spaced apart and forming independent chambers at the 55 opposed ends of said heat chamber, means for carrying carcasses progressively through said chambers, and flues leading from said chambers.

60 2. A hog singer, comprising a horizontal furnace having a longitudinally centrally arranged heat chamber, separate compartments at the ends of said heat chamber, water cooled doors arranged between the

heat chamber and the separate end compartments, doors at the outer sides of said end compartments, a trackway extending longitudinally and centrally through said furnace past said doors, means for carrying carcasses along said trackway through the furnace.

65 3. A hog singer, comprising a longitudinally extending horizontal furnace having closed compartments at the ends, a trackway extending directly through said furnace and closed compartments, an endless chain having one side thereof extending through the furnace parallel with and adjacent to the trackway, means for supporting carcasses from said trackway, and means on said endless chains for engaging said supporting means to move the same along the trackway.

70 4. In a hog singer, the combination with a horizontal furnace having a trackway extending therethrough, of a plurality of hinged frames arranged at either side of the furnace and in alignment with one end thereof, cylindrical rotating scraper brushes mounted in the inner ends of said frames, spring means for forcing said frames together to exert an inward yielding pressure, 90 and an endless conveyor extending through the furnace and past said brushes.

75 5. A hog singer, comprising a horizontal furnace having water pipes extending transversely thereof and connected to common leads at the ends, a water pipe extending longitudinally of the furnace and connected to said cross pipes; spray nozzles connected with said longitudinal water pipe and arranged outside of and in central alignment with the furnace, a trackway extending through the furnace arranged below and extending past said spray nozzles, and means for travelling the carcasses on said trackway through said furnace and past 100 said spray nozzles.

80 6. A hog singer comprising a horizontal furnace, a water pipe extending through and supported within said furnace, means for conveying water to said pipe at suitable 110 points in its length, and a trackway secured to and supported by said water pipe extending through said furnace.

85 7. In a hog singer, a horizontal furnace, a water pipe extending through said furnace, spraying nozzles arranged beyond said furnace above said water pipe and receiving the water therefrom, a plurality of supply pipes extending transversely of the furnace connected with and adapted to support 115 said water pipe therewithin, and a trackway secured to and supported by said water pipe and extending past said sprayers.

THOMAS OLSEN.
JOHN W. MAY.
